UNITED STATES PATENT OFFICE.

ALAN ERNEST LEOFRIC CHORLTON, ROLLO AMYATT DE HAGA HAIG, AND HELMUT JOHN STIEGER, OF LONDON, ENGLAND.

WING FOR AIRCRAFT.

Application filed July 16, 1928, Serial No. 293,094, and in Great Britain December 5, 1927.

This invention relates to wings for aircraft, and more particularly to cantilever wings in which a spar or spars projecting from a fuselage support the wing formed 5 around such spar or spars.

Spars employed as cantilevers in monoplane wings, are required to take not only the stresses due to the vertical and horizontal bending moments and combinations 10 of these stresses, but also torsional stresses which tend to twist the wing, and this has necessitated the employment of a spar or pair of spars of considerable width, which, owing to the limitation of wing depth, have been 15 difficult to brace satisfactorily against torsion stresses.

According to this invention, a spar is constructed of a depth permissible by the thickness of the wing and of any convenient 20 width. At suitable positions along the spar opposed pyramid bracings or staying bays are formed projecting fore and aft from the spar with the bases of the pyramids coinciding. The apices of the pyramids are 25 held apart by struts passing transversely through the spar. Two pairs of tension members form the edges of each pyramid and connect the apex of the pyramid to the upper and lower booms or members of the 30 spar.

In the accompanying drawings:

Figure 1 is a diagrammatic section of a wing of an aircraft containing a spar constructed in accordance with this invention.

Figure 2 is a diagrammatic perspective view of the same spar.

The spar is illustrated in girder form, A being the upper boom, B being the lower boom and C representing the web of the 40 girder. The pyramid bracings will be seen to form staying bays on opposite sides of the girder and are composed of struts D, D.

The tension members are illustrated in pairs, E, E¹, and F, F¹ forming one bay, and G, G¹ and H, H¹ forming the opposite 45 bay.

The strut D passes through an aperture C¹ in the web C and is thus free and unconnected to the web C, or to the spar, except 50 through the tension members E, E¹, F, F¹, G, G¹, H, H¹.

The tension members are illustrated in the drawings as wires, but it is obvious that tubes or other more rigid connections may 55 be used in the place of the said wires.

K is a longitudinal wire connecting the ends of the struts D of the spar on one side thereof, and L is a similar wire connecting the other ends of the struts D on the opposite side of the spar. 60

The struts which maintain the apices of the pyramids apart, may be formed by straight poles or triangular frames, and when the centres of the pyramids coincide with the ribs or with frames arranged in 65 the direction of the chord of the wing, such ribs or frames may be utilized after being suitably strengthened for supporting the apices of the pyramids and taking the tension of the tension members located on the 70 edges of the said pyramids.

Pyramid staying means of the character above referred to, may be located in successive bays throughout the span of the spars, and the bays may overlap if required 75 up to any desired degree. The bays may also be made in duplex form with two pyramids above and below in each bay. These wires K and L by maintaining the distance apart of the apices of the pyramids, resist 80 bending stresses caused by drag on the wing in flight.

In the application of the invention, the tension members are conveniently made of wire, and it will be clearly recognized that 85 the tension members comprising the bays nearest to the fuselage will be required to support greater stress than the wires comprising tension members in the outer bays away from the fuselage. The thickness of 90 the wires should therefore be chosen in accordance with the distance of the bay from the centre of the machine, larger gauge wires being used near the fuselage and less gauge wires being used in the outer bays. 95

What we claim as our invention and desire to secure by Letters Patent is:—

1. Cantilever spars for aircraft adapted to take bending stresses and torsional stresses, comprising in combination, upper and lower booms, a web attached to and holding such booms apart, and pyramid bracings constituting bays on opposite sides of the girder, each opposed pair of bays consisting of a compression member passing 100 transversely through the said web, and tension members connecting each end of such compression member to the booms. 105

2. Cantilever spars for aircraft adapted to take bending stresses and torsional 110

- stresses, comprising in combination, upper and lower booms, a web attached to and holding such booms apart, and pyramid bracings constituting bays on opposite sides 5 of the girder each opposed pair of bays consisting of a compression member passing transversely through the said web, and four tension members connecting each end of such compression member to the booms.
- 10 3. Cantilever spars for aircraft adapted to take bending stresses and torsional stresses, comprising in combination, upper and lower booms, a web attached to and holding such booms apart and pyramid bracings constituting bays on opposite sides 15 of the girder each opposed pair of bays consisting of compression supports projecting on opposite sides of the girder and tension members connecting the apices of the compression supports to two separated points on each boom such separated points being located on the booms on opposite sides of a plane containing both apices and perpendicular to the main axis of the spar.
- 20 4. Cantilever spars for aircraft adapted to take bending stresses and torsional stresses, comprising in combination, upper
- and lower booms, a web attached to and holding such booms apart, and pyramid bracings constituting bays on opposite sides 30 of the girder each opposed pair of bays consisting of struts passing transversely through the web of the spar and projecting on opposite sides of the girder, and tension members connecting the opposite ends of the 35 said strut to separated points on each boom.
5. Cantilever spars for aircraft adapted to take bending stresses and torsional stresses, comprising in combination, upper and lower booms, a web attached to and 40 holding such booms apart, and pyramid bracings constituting bays on opposite sides of the girder each opposed pair of bays consisting of struts passing transversely and freely through the web of the spar and projecting on the opposite sides of the girder, and tension members connecting the opposite ends of the said strut to separated 45 points on each boom.

In witness whereof we have hereunto set 50
our hands.

ALAN ERNEST LEOPRIC CHORLTON.
ROLLO AMYATT de HAGA HAIG.
